(Cl. D61—1)

To all whom it may concern:

Be it known that I, Albert Drucker, a citizen of the United States, residing at Chicago, in the county of Cook and State of Illinois, have invented a new, original, and ornamental Design for a Photographic Enlarger, of which the following is a specification, reference being had to the accompanying drawing, forming a part thereof.

The figure is a perspective view of a photographic enlarger, showing my new design.

I claim:

The ornamental design for a photographic enlarger, substantially as shown and described.
